UNITED STATES PATENT OFFICE.

FREDERICK C. SCHRAMM, OF NEW ORLEANS, LOUISIANA, ASSIGNOR OF THREE-FOURTHS TO AUGUST J. CLAVERIE AND ONE-FOURTH TO CLAUDE A. VILLARS, BOTH OF NEW ORLEANS, LOUISIANA.

ACETYLENE-GAS GENERATOR.

1,142,206.

Specification of Letters Patent. Patented June 8, 1915.

Application filed July 14, 1914. Serial No. 850,878.

To all whom it may concern:

Be it known that I, FREDERICK C. SCHRAMM, a citizen of the United States of America, residing at New Orleans, in the 5 parish of Orleans and State of Louisiana, have invented certain new and useful Improvements in Acetylene-Gas Generators, of which the following is a specification.

The present invention relates to improvements in acetylene gas generators and is directed especially to the feeding device which is of the carbid feed pop valve type of generator.

The primary object of the invention is to 15 provide in an acetylene gas generator, an improved feeding device by means of which the carbid is fed from the hopper to the generating chamber, and the feeding mechanism is actuated from the movement of the 20 gas bell through the medium of suitable connections as will be hereinafter fully set forth.

A further object of the invention is to 25 provide a simple and automatic cut-off in the feeding device, and to further improve the construction and operation of acetylene gas generators in their general construction. The invention consists in certain novel 30 combinations and arrangements of parts of the carbid feed and actuating mechanism as fully set forth hereinafter and claimed.

In the accompanying drawings I have 35 illustrated one complete example of the physical embodiment of my invention constructed according to the best mode. I have so far devised for the practical application of the principles of the invention, but it will be understood that the invention is susceptible of change, and that alterations and 40 changes may be made within the scope of my claims without departing from the spirit of the invention.

Figure 1 is an elevation of an apparatus embodying the novel features of my invention, parts being broken away, for convenience of illustration. Fig. 2 is an enlarged detached sectional view of the feed hopper, showing the feeding device and the actuating device for the feeding mechanism. 50 Fig. 3 is a further enlarged detail view of the actuating device for the feed mechanism.

In the preferred embodiment of my invention as illustrated in the drawings, I have shown a two-compartment machine or

apparatus for generating acetylene gas. 55 The tank 1 is the generating chamber, and the tank 2 is designed to receive the gas retainer or gas bell 3. The general construction of these tanks and the bell, is of the usual type, except that the generating chamber 1 has an inclined floor 4, and an agitator blade 5 is supported within the generating chamber just above the bottom 4 so that it may be swung to and fro in order to stir up or agitate any accumulated sediment 60 upon the bottom of the generating chamber. This agitator is supported upon a rod 6 formed with an upper bent handle portion 7, and revoluble in brackets or bearings 8 attached to the outer surface of the wall of 70 the gas generating tank. By means of the handle 7 the blade 5 may be agitated, and the sediment which accumulates upon the inclined bottom 4 may be stirred up or caused to fall into an auxiliary chamber 9 75 which has a clean out pipe 10 and valve 11. This chamber 9 is formed by the wall 12 which is preferably attached in suitable manner to the outer surface of the wall of the chamber 1, and is open at the top. An 80 over-flow opening 13 is provided near the upper end of this chamber 9, and from this over-flow opening, excess water may pass, in case an abnormal quantity should be allowed to enter the tanks 1 and 2. The 85 water line is indicated by the letters W L in Fig. 1. The gas bell 3 is adapted to rise and fall with the difference in gas pressure within the bell, and the usual rods 14, which are connected by a cross arm 15, are fixed 90 to the upper end of the tank 2 to guide the bell through the medium of the guide rollers 16 which are supplied from the gas bell by means of the spring arms 17.

The hopper or carbid holder 18 is located 95 directly above the generating chamber 1, and is provided with an upper conical portion 19, and a similar lower conical portion 20, the latter terminating at its lower end in a valve seat 21. A hood 22 connects the 100 hopper with the generating chamber or tank 1, and the gas inlet pipe 23 extends from this hood which forms a dome to the generating chamber, to the tank 2 and gas bell 3, as shown by dotted lines in Fig. 1.

A gas washer 24 and filter 25 are employed within the gas bell, but these features are not claimed as part of the present

invention. The gas supply pipe 26 leads from the filter 25 out through the bottom of the tank 2, to the service pipe, and thence to the burners as usual.

5 An automatic escape device is provided in connection with the tank 2 and the gas bell, which includes a perforated tube 27 fixed to the gas retainer, and an outlet pipe 28 fixed with relation to the tank 2. This

10 tube and outlet pipe telescope each other, and it will be apparent that should the gas bell rise too high, the gas will be permitted to pass through this perforated tube and out through the escape pipe 28 to the atmosphere.

15 As before stated, the generator is equipped with carbid feed of the pop valve type, and the pop valve or feed valve is indicated by the numeral 29 in position to co-act with the 20 valve seat 21 in the bottom of the hopper 18. The valve 29 is carried on the vertical stem 30, which is centrally located and vertically reciprocated within the hopper 18. The stem is passed through a plate 31 which 25 is supported by arms 32 from the bottom of the hopper 18, and forms a closed perforated bottom for the feed tube 33. This tube 33 is inclosed within the hopper, and has a cap 34 closing its upper end. This cap is 30 designed to act as a closure against the entrance of carbid, and the interference of the carbid with the feeding mechanism, when the carbid is fed or supplied through the opening 35 which is closed by the plug 36 35 in the top of the hopper.

35 The valve stem 30 is screwed into a feed rod 37, and this rod has pivoted thereto a link 38 which in turn is pivoted on the crank arm 39, fixed on the crank shaft 40. This 40 crank shaft, as clearly seen, extends within the hopper, and also projects out over the gas bell 3, and is supported to revolve in the wall of the hopper and also in a bearing 41 which is fixed to the cross bar 15 above the 45 gas bell. The outer end of this crank shaft is equipped with a second crank arm as 42, and this arm carries a grooved roller 43 which is adapted to contact with, and be ridden down, by an operating arm 44. This 50 operating arm, which extends at right angles to the crank shaft 40, is rigidly supported from the bell rod 45, and the bell rod is centrally located and fixed to the gas bell 3, to project upwardly to a suitable altitude. The operating arm 44 is provided 55 with a collar 46 fitted over the end of the bell rod 45, and a thumb screw 47 is employed to secure the operating rod against a pin 48 in the bell rod 45. Near its junction with the bell rod, the operating arm is 60 formed with a curved portion 44' adapted especially to engage the roller 43 at the initial contact of these parts.

65 On the crank shaft 40, a counter-acting weight 49 is suspended to close the valve 29.

This weight is adjustable on the arm 50, and the arm 50 is adjustable on the crank shaft 40, set screws 51 and 52 being employed for the purpose. As thus described, it will be understood that the valve 29 is opened when 70 the gas bell descends to a certain predetermined level, and that it is positively closed by means of the counter-acting weight 49 when it ascends to the normal level.

A cushioning spring 53 is supported upon 75 the perforated plate 31, and surrounds the stem 30. This spring is designed to take off the weight gradually from the gas bell, thereby reducing the gas pressure accordingly. For instance, if all the carbid has 80 been exhausted from the hopper, the bell 3 descends toward the bottom of the tank 2, the lower end of the rod 37 will eventually engage the outer end of the coil spring 53, and in this manner the weight of the bell is 85 gradually taken up, and the lights which are fed from the supply pipe will gradually diminish.

90 Preferably I employ a reserve carbid holder as 54, located at a convenient position within the hopper 18, and this holder which is open at the bottom, is controlled from the outside by means of a handle 55 and the stem 56, by means of which the valve 57 is turned to release the carbid in the holder 54. 95 This reserve carbid holder is designed especially to avoid recharging the machine at night in case the carbid in the main hopper should become exhausted. After all the 100 carbid is exhausted or consumed from the hopper 18, all lights will gradually grow dim, and this will be sufficient notice of the necessity of calling upon the reserve carbid, which may be done, and a sufficient supply 105 of gas generated to last until it is convenient to replenish the supply in the main hopper.

110 In using the generator, it is set for operation as follows: The thumb screw 47 and operating arm 44 are first removed, and the tanks 1 and 2 are filled with water until they overflow through the opening 13. The hopper 18 and the reserve carbid holder 54 are both filled with carbid. The counterweight 50 which holds the valve 29 closed within the seat 21, is now lifted, permitting a small 115 quantity of carbid to fall into the water in the generating chamber 1. The gas bell will rise as the gas is generated, at least until the outer end of the bell rod 45 has passed the roller 43, and then the operating arm 44 is placed over the upper end of the bell rod, and clamped thereon by means of the thumb nut 47. The apparatus is now ready to operate automatically. The feed of carbid is 120 prevented by the valve 29, and the valve is held closed by the weight 49. As the gas is consumed in the gas bell, it descends and the operating arm 44 in its descent encounters the roller 43. The first contact of the arm 44 with the roller 43 is at the curved portion 125 130

44', and a continued contact of these parts causes the arms 44 to ride downwardly to roller 43 and turn or rock the crank shaft 40 through the medium of the crank arm 42. 5 The rocking of the crank shaft turns the crank arm 39 downwardly and depresses the link 38, rod 37, and stem 30, and in this manner the valve 29 is adjusted so that the carbide may fall through the seat 21 into the gas generating tank 1. After the gas bell has risen, counter-weight 49 gradually rocks the crank shaft 40 and returns the valve 29 to closed position. This movement is kept up automatically as long as the supply of carbide in the hopper 18 remains unexhausted.

Having thus fully described my invention, what I claim as new and desire to secure by Letters Patent, is:— 20 1. In an acetylene gas generator, the combination with the hopper having a valve

opening therein, of a valve adapted to close said opening, a stem on the valve and a rock shaft operatively connected together, and means for rocking said shaft, and a ^{sup-25} supported spring coiled about said stem adapted to cushion the movement of said rock shaft.

2. The combination in an acetylene gas generator, with the carbide feed hopper having a valve opening, and a gas bell, of a ³⁰ valve with its stem supported in the hopper, a rock shaft for reciprocating said stem, an operating arm carried by the gas bell, and an anti-friction roller on the rock shaft, and a supported spring about the valve stem for ³⁵ cushioning excess movement of the gas bell.

In testimony whereof I affix my signature in presence of two witnesses.

FREDERICK C. SCHRAMM.
